UNITED STATES PATENT OFFICE

ABRAHAM M. ADELSON, OF BOSTON, MASSACHUSETTS

GARMENT HANGER

Application filed August 2, 1927. Serial No. 210,157.

This invention relates to garment hangers, and has for its object to provide a novel garment hanger by which a dress may be securely supported.

5 My improved garment hanger is provided with a supporting member having free ends on which the shoulder portions of a dress or other garment may be supported, and a retaining member arranged to cooperate with 10 the supporting member in retaining the garment securely on the supporting member.

In order to give an understanding of my invention, I have illustrated in the drawing a selected embodiment thereof, which will now 15 be described, after which the novel features will be pointed out in the appended claims.

In the drawings Figure 1 is a view illustrating my improved garment hanger and the manner in which it is used.

20 Figure 2 is a similar view with part broken out, showing the hanger with the retaining member raised, and with the supporting member in position to receive a garment.

Figure 3 is an enlarged sectional view 25 on the line 3—3 Fig. 1.

Figure 4 is a fragmentary sectional view showing the manner in which the retaining member is held in raised position.

My improved garment hanger comprises 30 a supporting member having free ends 2 on which the shoulder portion of a garment may be supported. This supporting member 1 has rigid therewith an upstanding post 3, from which rises a hook member 4 by which 35 the garment hanger may be suspended.

5 indicates a portion of the garment which is supported by the hanger, this garment being of the sleeveless variety. The garment is supported by the hanger in usual way by 40 placing the shoulder portions 6 of the garment over the free ends 2 of the supporting member.

One feature of my present invention relates 45 to novel means for retaining the shoulder portions of the garment on the supporting member 1. Where a garment of this style is hung on an ordinary garment supporter, the shoulder portions 6 are apt to slip off from the ends of the supporting arms.

50 My invention, however, provides means

for preventing this, and this is accomplished by providing a retaining member 7 which cooperates with the supporting member 1 to hold the shoulder portions of the garment in position on the arms of said supporting member. This retaining member 7 preferably has a shape similar to that of the supporting member 1, and it is slideably mounted in the post 3, so that it can be moved toward and from the supporting member 1. It is also acted upon by a spring which normally tends to carry it into operative position. Situated between the supporting member 1 and the retaining member 7 at the ends thereof are stops or spacers which serve to hold the supporting member and retaining member slightly separated when the retaining member is in operative position. These stops or spacers are indicated at 18, and they may be of felt or any other material, and may 60 be secured either to the top edge of the supporting member, or to the bottom edge of the retaining member. In either event, when the garment is placed on the hanger, the shoulder portions 6 thereof will be positioned inside 65 of the stops or spacers 18, so that when the retainer is in its operative position, the shoulder portions of the garment will be loosely received in the space 19 between the supporting member and the retaining member. With 70 this construction the shoulders of the garment will be loosely supported on the supporting member without danger of being injured by any clamping pressure of the retaining member, and the stops 18 which fill the 75 space between the supporting member and the retaining member at the ends of the hanger, will prevent the shoulder portions of the garment from slipping off from the supporting member.

As herein shown, the post 3 has a tubular formation, and it is provided with a transverse slot 8 through which the retainer member 7 extends. Said member has a pin 9 extending therethrough, the ends of which project into 85 slots 10 formed in the tubular member 3. The slot 8 is of sufficient size to receive the retaining member freely, and both the slots 8 and 10 are of sufficient length so that the retaining member can have considerable 90

movement toward and from the supporting member 1.

Situated within the tubular member 3 is a spring 11 which bears at one end against the retaining member 7, and at the other end is backed by a collar 12 which fills the upper end of the tubular member. This spring 11, therefore, tends to force the retaining member into clamping engagement with the stops 18, and yieldingly holds it in such position.

The retaining member 7 has a stem 13 secured thereto and rising therefrom, which stem extends up through the collar 12.

The supporting hook 4 is pivotally mounted on this stem, as shown at 14. The stem 13 projects a distance above the pivotal point 14, as shown at 15, and the shank of the hook 4 extends below the pivotal point 14 a slight distance, as shown at 16. The hook 4 not only forms a means for suspending the garment hanger, but also, because of its pivotal connection with stem 13, forms a means for raising the retaining member 7 into its elevated or open position, as shown in Fig. 2, whenever a garment has to be placed on the hanger or removed therefrom.

In using the device a person may grasp the supporting member 1 or post 3 with one hand, and pull upwardly on the hook 4 with the other, this operation raising the retaining member 7 into the position shown in Fig. 2, and thereby compressing the spring 13. When the retaining member has been thus raised, it may be retained in its raised position by swinging the hook member 4 downwardly into a horizontal position, as shown in Fig. 2, it being understood, of course, that before this can be done the retaining member will have to be raised sufficiently so that the pivotal point 14 will be above the collar 12 of the post 3.

When the hook member 4 has been thus swung down into its horizontal position, the shank thereof will lie across the top of the collar 12, and will thus lock or retain the member 7 in its raised position against the action of the spring 13. The ends 2 of the supporting member are now free to have a garment placed thereon, and if the garment is a dress, or a garment of the type shown in Fig. 1, the ends 2 of the supporting member will be inserted into the shoulder portions of the garment through the neck thereof.

After the garment has been hung on the supporting member 1, the member 7 is released and is then allowed to move into its operative position, as shown in Fig. 1, in which position it engages the stops 18. This release of the clamping member may be effected by simply swinging the hook 4 upwardly until the shank 17 is parallel with the stem 13, and in line with the opening in the collar 12. As soon as this position has been reached, the shank 17 of the hook may pass downwardly through the collar 12, and

the spring 11 will automatically move the member 7 into its operative position.

It will thus be seen that when a garment of the type shown in Fig. 1 is supported on the garment hanger, the shoulder portions 6 of the garment will be freely received in the space 19 between the members 1 and 7, and the stops 18 will prevent the said shoulder portions from slipping off from the supporting member. Since the said shoulder portions are freely received in the space 19, there is no danger that even the most delicate fabric will be injured by pressure of the member 7 thereagainst.

My improved garment hanger can also be used for supporting a coat or other garment in addition to a dress, for after a dress has been placed on the hanger, as shown in Fig. 1, it is possible to place a coat or any other garment over the member 7, as in the case of an ordinary garment hanger, and this can be done without in any way disturbing the dress 5.

I claim:

1. In a garment hanger, the combination with a supporting member having free ends on which a garment may be hung by its shoulder portions, of a tubular post rising from said supporting member, a rigid retaining member for retaining the garment on the supporting member, and a spring enclosed in the post for yieldingly holding the retaining member in operative position.

2. In a garment hanger, the combination with a supporting member having free ends on which a garment may be hung, of an upstanding tubular slotted post rising from the supporting member, a rigid retaining member extending through the slot of the post and movable bodily toward and from the supporting member, and a spring acting on said retaining member and yieldingly holding it in position to lock the garment to the supporting member.

3. In a garment hanger, the combination with a supporting member having free ends on which a garment may be hung, of a tubular post rising from the supporting member, a retaining member slideably mounted on said post and adapted to retain the garment on the supporting member, and a spring situated within the post and yieldingly holding the retaining member in operative position.

4. In a garment hanger, the combination with a supporting member having free ends on which a garment may be hung, of a tubular post rising from the supporting member, said post having a slot, a retaining member extending through said slot and movable toward and from said supporting member, a stem rising from the retaining member, a supporting hook pivoted to the stem, and a spring within the tubular post which tends to hold the retaining member yieldingly in operative position.

5. In a garment hanger, the combination with a supporting member having free ends on which a garment may be hung, of a tubular post rising from the supporting member,
5 said post having a slot, a retaining member extending through said slot and movable toward and from said supporting member, a stem rising from the retaining member, a supporting hook pivoted to the stem, and a
10 spring within the tubular post which tends to hold the retaining member yieldingly in operative position, the pivotal point of the hook being so situated that it is above the post when the retaining member is raised,
15 whereby the retaining member may be held in its raised position by turning the hook into a horizontal position in engagement with the top of the post.

6. In a garment hanger, the combination with a supporting member having free ends on which a garment may be hung by its shoulder portions, of a tubular post rising from the supporting member, a retaining member for retaining the garment on the
20 supporting member, a spring enclosed within the post, and acting against the retaining member to hold it yieldingly in operative position, and a supporting hook connected to the retaining member.

30 In testimony whereof, I have signed my name to this specification.

ABRAHAM M. ADELSON.
